UNITED STATES PATENT OFFICE.

ALBERT BLIST, OF LOS ANGELES, CALIFORNIA.

DOOR-CHECK.

1,111,291.

Specification of Letters Patent. Patented Sept. 22, 1914.

Application filed June 22, 1914. Serial No. 846,704.

To all whom it may concern:

Be it known that I, ALBERT BLIST, a citizen of the United States of America, residing at Los Angeles, county of Los Angeles, State of California, have invented a certain new and useful Door-Check; and I do hereby declare the following to be a full, clear, and exact description of the invention, such as will enable others skilled in the art to which it appertains to make and use the same.

This invention relates to an improved door check, and it may be said to consist in the provision of the novel features and in the novel and improved construction, arrangement, and combination of parts as will be apparent from the description and claims which follow hereinafter.

Objects of the invention are to provide a novel and improved door check which is simple in construction, economical to manufacture, strong and durable, easy to install, attractive in appearance, convenient to use, and effective in action.

Other objects and the advantages of the invention will be apparent from a careful consideration of the following description of the preferred construction embodying the invention, taken in connection with the accompanying drawings in which

Figure 1 is an elevational view of a door having the invention applied thereto; Fig. 2 is an enlarged broken cross-sectional view taken on the line 2—2 of Fig. 1; Fig. 3 is a similar view, the door being open but not shown; Fig. 4 is a front view of the door check; Fig. 5 is a side view of the door check; Fig. 6 is a cross-sectional view of the door check taken on the line 6—6 of Fig. 4; and Fig. 7 is a similar view with parts in changed position.

The frame of the device preferably consists of the angular plate 8 which has a portion thereof pressed inwardly to provide the spaced lugs 9. An inclined plate 10 has one end thereof pivotally mounted on a rod 11 which is secured to the lugs 9, and it has on the other end thereof a substantially inverted-U-shaped extension 12 having thereon the ears 13 formed with slots 14 therein. A coil spring 15 is disposed on a rod 16 which is mounted on the lugs 9, and it has one end portion thereof bearing against the angular plate 8 and had the other end portion thereof bearing against the extension 12 to normally press the extension 12 against

the rod or roller 17 which is suitably mounted on the lugs 9. A curved plate 18 is disposed in contact with the rod or roller 17 and has at its sides lugs 19 on which is mounted the rod 20 which passes through the slots 14. On the rod 20 is arranged a coil spring 21 which has one end thereof secured to the curved plate 18 and has its other end portion bearing against the extension 12.

In use, the jamb 22 may be provided with a mortise or recess adapted to accommodate the lugs 9 and the parts carried thereby, and the angular plate 8 may be secured to the jamb 22 by means of screws 23 fitted in openings 24 in the angular plate 8. When the door 25 is being closed it first contacts with the inclined plate 10 and moves the plate 10 inwardly against the action of the spring 15. The inward movement of the plate 10 causes an inward movement of the extension 12 and the latter—when the ears 13 pick up the rod 20—causes an inward movement of the rod 20 and of the curved plate 18 which is connected to the rod 20 by the spring 21. The curved plate 18 moves gradually in contact with the rod or roller 17, and the door 25 gradually slips by the inclined plate 10 and then abuts against and moves inwardly the curved plate 18. It will be seen that the device permits of the use of comparatively light springs, and operates effectively to exert a gradual and smooth checking action on the door when the latter is being closed.

The construction which has been particularly illustrated and described admits of many minor changes and modifications, wherefore the right is reserved to all such changes and modifications as do not depart from the spirit and scope of the invention which is defined in the appended claims.

I claim:

1. A door check including a frame, a rod on the frame, a spring-pressed inclined plate pivotally mounted on the rod and provided with an extension having slots therein, a second rod on the frame, a third rod passing through said slots, a curved plate mounted on the third rod and disposed in contact with the second rod, and a coil spring arranged on the third rod and having one end portion thereof secured to the curved plate and having the other end portion thereof bearing against said extension.

2. A door check comprising a frame, a

rod on the frame, an inclined plate having one end thereof pivotally mounted on the rod and provided with a substantially inverted -U- shaped extension having ears thereon, said ears provided with slots, a second rod on the frame, a coil spring arranged on the second rod and having one end portion thereof in contact with the frame and having the other end portion thereof bearing against said extension, a third rod mounted on the frame, a fourth rod passing through said slots, a curved plate mounted on the fourth rod and disposed in contact with the third rod, and a coil spring arranged on the

fourth rod and having one end portion thereof secured to the curved plate and having the other end portion thereof bearing against said extension.

In testimony whereof, I have signed my name to this specification in the presence of two subscribing witnesses at Los Angeles, county of Los Angeles, State of California, this 11th day of June, A. D. 1914.

ALBERT BLIST.
